WINDOW BOX SUPPORT

Richard R. Hertzel, 19 Bruen Court,
Rensselaer, N.Y. 12144

Filed Feb. 21, 1974, Ser. No. 444,214

Term of patent 14 years

Int. Cl. D8—08

U.S. Cl. D8—242

FIG 1

FIG 3

FIG 4

FIG. 2

FIG. 5

FIG 6

FIG. 1 is a front perspective view of a window box support showing my design;

FIG. 2 is a side view of the window box support, the other side being substantially identical thereto;

FIG. 3 is a top plan view thereof;

FIG. 4 is a rear elevation thereof;

FIG. 5 is a front elevation view thereof; and

FIG. 6 is a bottom plan view thereof.

The broken lines in FIG. 1 are for illustrative purposes only.

I claim:

The ornamental design for window box support, substantially as shown and described.
